RAILWAY SIGNALING SYSTEM

Crawford E. Staples and Herman G. Blosser,
Pittsburgh, Pa., assignors to The Union Switch
& Signal Company, Swissvale, Pa., a corpora-
tion of Pennsylvania

Application July 24, 1943, Serial No. 496,032

13 Claims. (Cl. 246—39)

Our invention relates to a coded railway signaling system.

In track stretches in which coded energy is employed to govern movement of traffic through the track stretch it is preferred to transmit this energy over the track rails where the track sections into which the stretch is divided are relatively long. Where a block section includes an intersection with a highway or a track switch it may be necessary to divide the block section into a plurality of relatively short track sections, and in such situations it has been proposed to transmit the coded signal control energy around these short sections by means of a line circuit.

In situations of the type described the short track sections may be provided with track circuits employing steady energy to detect occupancy of the sections, while the track relays of these short track sections may govern the line circuit over which coded energy is supplied to control traffic in the block section in the rear.

In track stretches through which are operated locomotives equipped with cab signal apparatus it is necessary to supply to the rails of each of the track sections alternating current energy coded at rates determined by traffic conditions in advance.

It is an object of this invention to provide for the track sections equipped with steady energy track circuits in a situation of the type described coded alternating current supply means operated by coded energy supplied over the line circuit extending around the track sections.

A further object of the invention is to provide improved means of the type described and employing a plurality of coding relays operated from the line circuit, but which is arranged so that only one coding relay is operated from the line circuit at one time to thereby reduce the amount of energy which must be transmitted over the line circuit and preventing interference by the coding relays with the operation of each other.

Another object of the invention is to provide means of the type described which is arranged so that the track relays of the various track sections control connection of the coding relays with the line circuit so that as a train enters each track section the line circuit is connected to the coding relay associated with that track section and is disconnected from the coding relays for the track sections in the rear.

A further object of the invention is to provide an improved system in which master code is transmitted over a line circuit and which in-

cludes means to supply feed-back energy over the line circuit together with means responsive to this feed-back energy for performing selected functions.

5 Another object of the invention is to provide in a signaling system in which spaced impulses of master code are supplied to a pair of conductors at one end thereof improved means for supplying impulses of feed-back energy to the conductors at the other end thereof in the intervals between impulses of master code.

A further object of the invention is to provide an improved signaling system of the type described and in which the energy impulse induced in the winding of the relay responsive to master code supplied over the conductors on termination of an impulse of master code is supplied over the conductors and operates the feed-back detector relay.

20 In practicing our invention we divide a block section into appropriate subsections, hereinafter called track sections, and provide a track circuit employing steady energy for each of the track sections, while we also provide for each of these 15 track sections a track transformer for supplying alternating current cab signal control energy to the section rails. In addition, we provide a line circuit coextensive with the track sections and controlled by the track relays for those sections, 25 while means governed by traffic conditions in advance is provided for supplying coded energy to this line circuit. A first code following relay located at the end of this line circuit is energized by current supplied over this line circuit and 30 controls the supply of coded energy to the track stretch in the rear, while means is provided for supplying feed-back energy over the line circuit to control functions at the exit end of the block section. A second code following relay is located 35 at an intermediate point in the block section and when the section in the rear of the second code following relay is occupied the supply of coded energy over the line circuit to the first code following relay is cut off and the second code following relay is connected to the line circuit and 40 is operated to cause coded alternating current cab signal control energy to be supplied to the occupied track section, while the supply of feed-back energy over the line circuit is cut off.

45 50 In some species of the invention the inductance of the code following relay is such that the impulse of energy induced in the relay winding on interruption of the supply of energy to the relay winding is of such magnitude as to be effective to operate the feed-back detector relay, and use

of this energy for this purpose eliminates the need for an impulse relay and associated apparatus to control the supply of feed-back energy to the line circuit.

We shall describe one form of railway signaling system embodying our invention, together with several modifications thereof which we may employ, and shall then point out the novel features thereof in claims.

In the drawings,

Fig. 1 is a diagram of a stretch of railway track equipped with a signaling system embodying our invention, and

Figs. 2, 3, 4 and 5 are fragmentary diagrams showing modifications which we may employ.

Similar reference characters refer to similar parts in each of the several views.

Referring to Fig. 1 of the drawings, there is shown therein a stretch of railway track having track rails 1 and 2 over which traffic normally moves in the direction indicated by the arrow, that is, from left to right. The rails of the track stretch are divided by insulated joints 3 into block sections for signaling purposes. One complete block section, together with portions of the two adjoining block sections, is shown in the drawings.

The block section shown in the drawings includes an intersection with a highway R, and the rails of the block section are divided by insulated joints 3 into track sections to provide for control of the crossing signals XS which warn users of the highway of the approach of a train. As shown, there are track sections 7AT, 7BT, 7CT and 7DT, the section 7CT being a short section which includes the highway crossing and is provided so that on movement of a train in either direction through the track stretch operation of the crossing signals will be continued until the train clears the crossing. If this method of control of the crossing signals is not required, the section 7CT may be omitted and the sections 7BT and 7DT may adjoin.

A wayside signal designated S with an appropriate numerical prefix is located at the entrance end of each block section. These signals may be of any appropriate type, and as shown are of the color light type, each signal having a green or proceed lamp G, a yellow or caution lamp Y, and a red or stop lamp R. While the invention is illustrated and described in connection with a track stretch equipped with wayside signals, the invention is not limited to use in such situations, but is equally applicable to track stretches without wayside signals and in which traffic is governed solely by cab signals.

The block sections 8T and 8T may be equipped with coded track circuit apparatus of any appropriate design. One form of apparatus which may be employed in these sections is shown in our application for Letters Patent of the United States Serial No. 473,792, filed January 28, 1943.

Similarly, the section 7AT may be provided with coded track circuit apparatus of the type shown in our application identified above. However, if desired, the track section 7AT may be provided with track circuit apparatus of the type employed in sections 7BT and 7DT and described in detail below.

The track sections 7BT, 7CT and 7DT are provided with track circuits employing steady or non-coded energy. Each of these sections has a track battery connected across the section rails at one end of the track section, and a track re-

lay, designated TR with an appropriate prefix, connected across the section rails at the other end of the track section.

In addition, each of the track sections 7AT, 7BT, 7CT and 7DT is provided with a track transformer designated TT with an appropriate prefix. The track transformers are located at the exit end of the associated track section, and each of these transformers has its secondary winding included in the track circuit of the associated track section.

The track batteries for track sections 7AT and 7DT are located at the exit ends of these sections and the secondary windings of the track transformers for these track sections are connected in series with the track batteries.

The track relays for sections 7BT and 7CT are located at the exit ends of these sections, and the secondary windings of the track transformers for these sections are connected in multiple with the track relays. A resistor is included in series with each of the transformer secondary windings to reduce flow of direct current track circuit energy through the transformer secondary windings, while the windings of the track relays have such high impedance to alternating current that little energy supplied from the track transformers flows through the relay windings.

The highway crossing signals XS are controlled by relay XR which is governed in the manner well known in the art by slow releasing relays WS and ES, and by the track relays 7BTR, 7CTR and 7DTR.

The operation of relays XR, WS and ES to control the crossing signals XS is not a part of this invention, and in order to simplify the disclosure their operation will be omitted. A description of the operation of these relays may be found in application for Letters Patent of the United States Serial No. 463,733 of James J. Van Horn.

A pair of line wires 10 and 11 extend from the exit end of the block section to the exit end of track section 7AT, while means is provided for supplying master code and feed-back energy over this line circuit to control the supply of coded alternating current cab signal energy to the rails of the various track sections and to also control the supply of coded track circuit energy to track section 7AT.

A coding relay CR is located at the exit end of the block section and controls the supply of master code to the line wires 10 and 11, connection of line wires 10 and 11 to the line winding of feed-back detector relay AR, the supply of energy to the local winding of relay AR, and the supply of energy to the primary winding of track transformer 7DTT.

Means governed by traffic conditions in section 8T is provided for supplying coded energy to coding relay CR. This means includes a relay 8H which is controlled by traffic in section 8T so that its contact 12 is picked up or released according as section 8T is vacant or is occupied. When contact 12 of relay 8H is picked up it establishes a circuit controlled by a contact of code transmitter 180CT for supplying energy to coding relay CR so that at such times relay CR is operated at the 180 code speed. When contact 12 of relay 8H is released it establishes a circuit controlled by a contact of code transmitter 75CT so that at such times relay CR is operated at the 75 code speed.

The relay AR controls the supply of energy to slow releasing relay AP which governs the circuit

of the primary winding of track transformer 1BTT.

A coding relay CRA is located at the left-hand end of the line circuit, and is connected across the line wires 10 and 11 over back contacts 14 and 15 of impulse relay IRA. A contact 16 of relay CRA controls the supply of energy to the primary winding of impulse transformer IT, while energy is supplied from the secondary winding of this transformer to relay IRA. The relay IRA is of a type the contacts of which become picked up when and only when energy of a particular polarity is supplied to the relay winding, while the various elements of the combination are arranged so that energy of the polarity effective to pick up the contacts of relay IRA is supplied to relay IRA on release of the contacts of relay CRA. In addition, the various elements of the combination are proportioned so that the impulses of energy supplied to the relay IRA to pick up its contacts keep the relay contacts picked up only for periods somewhat shorter than the shortest of periods in the coded energy supplied to the relay CRA.

Coding relay CRA controls connection of track battery 1ATB and the secondary winding of track transformer 1ATT across the rails of section 1AT, while it also controls connection of the track winding of relay ARA across the section rails. In addition, relay CRA controls the supply of energy to the local winding of relay ARA. The relay ARA controls the supply of energy to relay APA which governs the supply of energy to the primary winding of track transformer 1ATT, and to the primary winding of the impulse transformer IT.

The track section 1AT has at the entrance end thereof a code following track relay 1ATR with which is associated a decoding transformer 1DT, code detecting relays 1AH and 1AJ, an impulse relay 1IR, and a feed-back battery 1AFB. The equipment at entrance end of section 1AT may be arranged as shown in Letters Patent of the United States No. 2,286,002 to Frank H. Nicholson and operates in the customary manner to control the lamps of signal 1S and to control the supply of coded energy to the section in the rear.

A coding relay CRB is located adjacent the highway intersection and controls the supply of energy to the primary windings of track transformers 1BTT and 1CTT. The track relays 1BTR and 1CTR control the line wires 10 and 11 and when both of these track relays are picked up energy is supplied over these line wires to coding relay CRA and relay CRB is disconnected from the line wires, while when either of these track relays is released the supply of energy over the line wires 10 and 11 to the relay CRA is interrupted and energy is supplied to relay CRB.

The track relay 1CTR controls the circuits of track transformers 1BTT and 1CTT so that the primary winding of transformer 1BTT is connected to the contact of coding relay CRB when relay 1CTR is picked up, and so that transformer 1CTT is connected to the coding relay contact when relay 1CTR is released.

Each location in the track stretch is provided with a suitable source of direct current, such as a storage battery, not shown, the terminals of which are designated B and C in the drawings.

The alternating current employed for cab signal control may be supplied from a suitable source, the terminals of which are designated BX and CX in the drawings.

The equipment is shown in the condition which it assumes when the track stretch is vacant. At this time track relays 1BTR, 1CTR and 1DTR are picked up and their contacts connect line wires 10 and 11 to coding relay CRA and interrupt the circuit of coding relay CRB. Accordingly, the contacts of relay CRB remain released and interrupt the circuits for supplying alternating current to transformers 1BTT and 1CTT, while relay CRA is operated by coded energy supplied over wires 10 and 11.

At this time relay 8H is picked up and its contact 12 establishes the circuit to supply energy of 180 code frequency to the coding relay CR and the contacts of relay CR pick up and release at the 180 code frequency rate.

When contacts 20 and 21 of relay CR are picked up line wires 10 and 11 are connected to terminals B and C of a source of direct current, and energy is supplied over wires 10 and 11, front contacts of track relays 1DTR, 1CTR and 1BTR, and back contacts 14 and 15 of relay IRA to coding relay CRA. Accordingly, the contacts of relay CRA pick up and its contact 22 interrupts the circuit of the track winding of relay ARA and connects the track battery 1ATB and the track transformer 1ATT across the rails of section 1AT. In addition, contact 23 of relay CRA establishes the circuit of the local winding of relay ARA and energy supplied to this winding causes contact 24 of the relay to move to its right-hand or reverse position in which it interrupts the circuit of relay APA.

The energy supplied from track battery 1ATB to the section rails feeds to the track relay 1ATR and picks up its contacts.

When the contacts of coding relay CR are picked up contact 26 establishes the circuit of the local winding of relay AR and energy supplied to this winding causes the relay contact 27 to move to its right-hand or reverse position in which it interrupts the circuit of the relay AP.

On release of coding relay CR the supply of energy to line wires 10 and 11 and to the local winding of relay AR is cut off, while contacts 20 and 21 connect the lower or line winding of relay AR across the line wires. On interruption of the supply of energy to line wires 10 and 11 the contacts of relay CRA release so that contact 16 interrupts the circuit for supplying energy to the upper portion of the primary winding of transformer IT and establishes the circuit for supplying energy to the lower portion of this winding. At this time an impulse of energy is supplied from the transformer secondary winding to the relay IRA and its contacts 14 and 15 pick up momentarily to interrupt the circuit of coding relay CRA and to connect wires 10 and 11 across the terminals of a source of direct current with the result that energy is supplied over line wires 10 and 11 and over back contacts 20 and 21 of coding relay CR to the line winding of relay AR. The polarity of the energy supplied to the line winding of relay AR is such that it causes the contact 27 of the relay to be moved to its left-hand or normal position in which it establishes the circuit of the relay AP.

Accordingly, as long as the block section is vacant, feed-back energy is supplied over line wires 10 and 11 to relay AR during the released periods of relay CR, and this energy causes the contact 27 of relay AR to establish the circuit of relay AP, while during the picked-up periods of relay CR its contact 26 establishes the circuit of 75 the local winding of relay AR and causes contact

27 to be moved to the position in which it interrupts the circuit of relay AP. The relay AP is of a type the contacts of which are slow to release so its contacts remain picked up during the periods in which the supply of energy to the relay winding is interrupted. Accordingly, contact 33 of relay AP interrupts the circuit for supplying energy to the lamps of signal 8S, while contact 34 of relay AP interrupts the circuit of the primary winding of track transformer 7DTT.

In addition, on release of the contacts of relay CRA, the supply of energy from battery 7ATB to the rails of section 7AT is cut off, while the track winding of relay ARA is connected across the rails of section 7AT. On interruption of the supply of energy from battery 7ATB to the section rails the contacts of the track relay 7ATR release and an impulse of energy is supplied from the decoding transformer 7DT to relay 7IR to pick up the contacts of this relay momentarily and thereby cause an impulse of feed-back energy to be supplied to the section rails. This energy feeds over back contact 22 of relay CRA to the track winding of relay ARA and causes contact 24 of the relay to move to its normal position to establish the circuit of relay APA. The relay APA is of a type the contacts of which are slow to release so its contacts remain picked up during the periods in which the supply of energy to the relay winding is interrupted and contact 35 prevents the supply of alternating current to the track transformer 7ATT and shunts the primary winding of the track transformer to thereby reduce impedance of the transformer secondary winding and reduce arcing at the contacts of relay CRA.

In addition contact 36 of relay APA maintains the circuit for supplying energy to the primary winding of impulse transformer IT so that the impulse relay IRA is operated to supply feed-back energy to the line wires 10 and 11.

As a result of code following operation of relay 7ATR energy is supplied through the decoding transformer 7DT to relays 7AH and 7AJ and they function in the usual manner to control the supply of coded energy to the rails of the adjacent track section in the rear and to control the signal 7S.

As long as the block section is vacant, therefore, relays APA and AP are picked up to prevent the supply of alternating current to track transformers 7ATT and 7DTT, while relay CRB is released and prevents the supply of energy to transformers 7BT and 7CTT.

Operation of equipment on movement of a train through the track stretch in the normal direction

When a train moving in the normal direction of traffic enters section 7AT track relay 7ATR is shunted with the result that relays 7AH and 7AJ release, while relay 7IR ceases to operate to supply impulses of feed-back energy to the rails of section 7AT. When the supply of feed-back energy to the rails of section 7AT is cut off the contact 24 of relay ARA is moved to its right-hand or reverse position by energy supplied to the local winding of the relay and it thereafter remains in that position so that the circuit of relay APA is interrupted. Accordingly, contact 35 of relay APA releases and alternating current energy is supplied to transformer 7ATT and thereafter energy is supplied from this transformer to the rails of section 7AT during each

picked-up period of the contacts of relay CRA. At this time the relay CRA continues to be supplied with coded energy of 180 code frequency so the alternating current energy supplied to the rails of section 7AT is coded at this rate and will operate the cab signal apparatus on the locomotive to provide the clear indication.

In addition, on release of relay APA its contact 36 interrupts the circuit of the primary winding 10 of impulse transformer IT so that energy ceases to be supplied through this transformer to relay IRA, and the contacts of relay IRA remain released with the result that impulses of feed-back energy are no longer supplied to the line wires 10 and 11. Accordingly, contact 27 of relay AR is moved to its right-hand or reverse position by energy supplied to the local winding of the relay and remains in that position so that the contacts of relay AP release, and contact 33 establishes 20 the circuit of the lamps of signal 8S, while contact 34 establishes the circuit of the track transformer 7DTT. The circuit for supplying energy to the track transformer 7DTT includes contact 37 of relay CR so the alternating current supplied to the rails of section 7DT is coded at the rate determined by the rate of operation of relay CR.

When the train advances into section 7BT track relay 7BTR releases and its contacts 38 and 39 cut off the supply of master code energy over line wires 10 and 11 to relay CRA and connect wires 10 and 11 to the winding of relay CRB. Accordingly, relay CRB is operated by energy of 180 code frequency supplied over line wires 10 and 11 and on each movement of contact 40 of relay CRB to its picked-up position energy is supplied over front contact 42 of track relay 7CTR to transformer 7BT to thereby cause coded alternating current to be supplied to the rails of section 7BT to operate the cab signal apparatus on the locomotive while the locomotive is in that section.

In addition, on release of relay 7BTR and resultant interruption of the supply of energy to relay CRA the contacts of this relay remain released so that coded energy is no longer supplied to the rails of section 7AT.

When the train advances into section 7CT track relay 7CTR releases and its contact 42 interrupts the circuit of transformer 7BT and establishes the circuit of the transformer 7CTT so that coded alternating current energy is supplied to the rails of section 7CT to operate the locomotive cab signal apparatus while the locomotive is in section 7CT.

In addition, when track relay 7CTR releases its contacts 48 and 49 connect line wires 10 and 11 directly to the coding relay CRB and thereby insure that as long as section 7CT is occupied the relay CRB will be operated by coded energy supplied over the line wires. At this time contacts 48 and 49 of relay 7CTR prevent supply of energy over line wires 10 and 11 to relay CRA so that relay CRA remains released and does not supply coded energy to the rails of section 7AT. This insures that signal 7S will continue to display its stop indication and that if a second locomotive enters section 7AT the cab signal equipment on the locomotive will display its stop indication.

When the train advances into section 7DT relay 7DTR releases and its contacts 52 and 53 interrupt line wires 10 and 11 to prevent the supply of coded energy over these wires to either relay CRA or CRB.

As previously explained, when the train entered

section 7AT and caused the supply of feed-back energy over the wires 10 and 11 to be cut off, relay AP released to cause coded alternating current energy to be supplied to the rails of section 7DT. Accordingly, when the train advances into section 7DT the coded alternating current supplied to the section rails operates the locomotive cab signal equipment.

When the train advances into section 8T relay 8H releases and changes the energy supplied to relay CR from 180 to 75 code frequency, while the signal 8S is caused to display its stop indication.

When the train vacates section 7AT track relay 7ATR remains released as relay CRA is not energized since the supply of energy thereto over line wires 10 and 11 is interrupted because of release of the track relay of one or more of the track sections in advance. Accordingly, relay 7AH remains released and maintains the display of the stop indication by signal 7S.

When the train vacates section 7BT track relay 7BTR picks up so that its front contacts 38 and 39 are closed. At this time supply of energy over line wires 10 and 11 to relay CRA is prevented since relays 7CTR and 7DTR are released so relay CRA remains released and does not cause coded energy to be supplied to section 7AT.

When the train vacates section 7CT track relay 7CTR picks up, but at this time the line wires 10 and 11 are interrupted by contacts 52 and 53 of relay 7DTR so relays CRA and CRB remain released.

When the train vacates section 7DT track relay 7DTR picks up and completes the circuit of the line wires 10 and 11 so that energy is supplied over these wires to relay CRA and it operates to supply energy to the rails of section 7AT. This energy operates track relay 7ATR to cause energy to be supplied through the decoding transformer 7DT to relays 7AH and 7IR. Accordingly, relay 7AH picks up to cause signal 7S to display its caution indication, while relay 7IR operates to supply impulses of feed-back energy to the section rails. This energy feeds to relay ARA and operates it to pick up relay APA and cut off the supply of energy to track transformer 7ATT and to establish the circuit of impulse transformer IT so that energy is supplied to relay IRA to operate it to supply impulses of feed-back energy to the line wires 10 and 11. The feed-back energy supplied to the line wires 10 and 11 feeds to relay AR and operates it to pick up relay AP and cut off the supply of energy to the lamps of signal 8S and to the track transformer 7DTT.

If, while the train under consideration is in section 8T, a second or following train enters section 7AT the supply of feed-back energy over the rails of this section will be cut off and relay APA will release to establish the circuit of the track transformer 7ATT, while the supply of feed-back energy to the line wires 10 and 11 is cut off so that relay AP releases and establishes the circuits of the lamps of signal 8S and of the track transformer 7DTT. At this time relay CRA is operated by energy of 75 code frequency so the alternating current supplied to the rails of section 7AT is coded at this rate and operates the locomotive cab signal apparatus to provide its caution indication. Similarly, as the train advances into sections 7BT, 7CT and 7DT the cab signal apparatus is operated by energy of 75 code frequency supplied to the rails of these sections.

Operation of equipment on movement of a train through the track stretch in the reverse of the normal direction

When a train moving in the reverse direction enters section 8T relay 8H releases and changes the energy supplied to relay CR from 180 to 75 code frequency with the result that there is a corresponding change in the energy supplied by relay CRA to the rails of section 7AT, and signal 7S is caused to display its caution indication.

When the train enters section 7DT track relay 7DTR releases and its contacts 52 and 53 interrupt line wires 10 and 11 so that relay CRA ceases to follow code and cuts off the supply of energy to the rails of section 7AT with the result that relay 7AH releases and causes signal 7S to display its stop indication.

At this time as the circuit of the line wires 10 and 11 is interrupted feed-back energy is not supplied to relay AR and it ceases to establish the circuit of relay AP. Similarly, as the track relay 7ATR is not supplied with coded energy, the relay 7IR does not operate to supply feed-back energy to the rails of section 7AT and relay 7ARA is not operated to establish the circuit of relay 7APA and it releases.

When the train enters sections 7CT and 7BT track relays 7CTR and 7BTR release and additionally prevent the supply of energy over the line wires 10 and 11 to relay CRA, while when the train enters section 7AT the rails of this section are shunted to prevent supply of energy to track relay 7ATR.

When the train vacates section 7DT coded energy is supplied to relay CRB over back contacts 48 and 49 of relay 7CTR and relay CRB operates to cause coded energy to be supplied through transformer 7ATT. When the train vacates section 7CT track relay 7CTR picks up and energy from line wires 10 and 11 is supplied over back contacts 38 and 39 of relay 7BTR to relay CRB, while coded alternating current energy is supplied to track transformer 7BTT.

When the train vacates section 7BT track relay 7BTR picks up and cuts off the supply of energy to relay CRB and causes energy to be supplied over the line wires 10 and 11 to the relay CRA. On the resultant supply of coded energy to relay CRA it operates, but energy is not supplied through transformer IT to relay IRA as the circuit of the primary winding of transformer IT is interrupted by contact 36 of relay APA. Accordingly, relay IRA remains released and does not supply feed-back energy to the line wires 10 and 11 and relay AR does not establish the circuit of relay AP. As a result relay AP remains released and maintains the circuits of the lamps of signal 8S and of transformer 7DTT.

On operation of relay CRA coded energy is supplied to the rails of section 7AT and when section 7AT is vacated this energy feeds to relay 7ATR and operates it so that relay 7AH picks up, while relay 7IR operates to supply feed-back energy over the section rails to relay ARA so that relay APA picks up to cut off the supply of energy to track transformer 7ATT and to establish the circuit to supply energy to the impulse transformer IT. Accordingly, relay IRA now operates to supply feed-back energy to the line wires 10 and 11 and this energy operates relay AR so that relay AP picks up and interrupts the circuits of the lamps of signal 8S and of the track transformer 7DTT.

From the foregoing it will be seen that when the track stretch is vacant master code energy is supplied over the line wires 10 and 11 and operates relay CRA to supply master code to the rails of section 7AT, while as long as the block section is vacant feed-back energy supplied over the rails of section 7AT operates relay ARA to energize relay APA so that it prevents the supply of energy to track transformer 7ATT and maintains the supply of energy to impulse transformer IT so that relay IR is operated to supply feed-back energy to line wires 10 and 11 and thus operate relay AR and energize relay AP to prevent the supply of energy to track transformer 7DTT and to the lamps of signal 8S. In addition, when the block section is vacant track relays 7BTR and 7CTR interrupt the circuit of relay CRB so that its contact interrupts the supply of cab signal control energy to sections 7BT and 7CT.

When a train enters section 7AT the supply of feed-back energy over the rails of section 7AT is cut off and relay APA releases to cause cab signal control energy to be supplied to the section rails, and to cut off the supply of feed-back energy to line wires 10 and 11 so relay AP releases and causes the signal 8S to be lighted and causes cab signal control energy to be supplied to the rails of section 7DT.

When the train advances into section 7BT track relay 7BTR releases and interrupts the supply of energy from line wires 10 and 11 to relay CRA and connects line wires 10 and 11 to relay CRB. Accordingly, relay CRA ceases to follow code so that coded energy is no longer supplied to section 7AT, while relay CRB is now operated so that coded energy is supplied to section 7BT or section 7CT.

It will be seen that the apparatus is arranged so that the coding relays CRA and CRB are not both connected to the line wires 10 and 11 at one time. As only one coding relay is connected to the line wires 10 and 11 at one time operation of the coding relays is positive, and these relays can be operated over relatively long line circuits with a minimum of line current. In addition, as only one coding relay is connected to the line wires at one time there is no possibility that the coding relays will interfere with each other. Accordingly, the coding relays will accurately respond to the coded energy supplied over the line wires and will cause coded energy of accurate code pattern to be supplied to the rails of the track sections.

Furthermore, as coding relay CRB is not connected to the line wires when coding relay CRA is being operated by energy supplied over these wires, there is no possibility that relay CRB will interfere with the impulses of feed-back energy supplied to the line wires as a result of operation of relay CRA.

Modification shown in Fig. 2

In the system shown in Fig. 1 the relay AR is provided with a local winding which is energized by current supplied over a local circuit when relay CR is picked up, while relay AR is provided with a separate line winding which is connected across the line wires 10 and 11 when relay CR is released. If desired the relay AR may have a single winding which is included in series with the line wires and Fig. 2 is a diagram showing such a modification.

Referring to Fig. 2, the relay AR is connected in series with the line wire 11 so as to be oper-

ated by both master code and feed-back energy supplied over the line circuit. When the contacts of relay CR are picked up master code energy is supplied to the line wires 10 and 11 and operates relays CRA and AR. The polarity of the energy supplied to the line wires is such that master code energy supplied to relay AR causes the relay contact 27 to be moved to its right-hand or reverse position in which it interrupts the circuit of relay AP.

On release of the contacts of relay CR the supply of master code energy to the line wires is cut off while connection is established between the line wires so that on picking up of relay IRA, and resultant supply of an impulse of feed-back energy to the line wires, this energy will flow through the winding of relay AR. The polarity of the feed-back energy is such that it causes contact 27 of relay AR to move to its left-hand or normal position in which it establishes the circuit of relay AP.

As long as the block section is vacant so that feed-back energy is supplied over the line wires 10 and 11 relay AR operates to maintain relay AP picked up and thus prevent the supply of cab signal energy to section 7DT and to prevent the supply of energy to the lamps of signal 8S.

When the block section is occupied the supply of feed-back energy over the line wires 10 and 11 is cut off and master code supplied to the line wires holds contact 27 of relay AR in its reverse position in which it interrupts the circuit of relay AP so relay AP releases.

The equipment is otherwise the same as that shown in Fig. 1 both in construction and operation.

Modification shown in Fig. 3

If desired the coding relay CRA may be connected in series with the line circuit, and Fig. 3 is a fragmentary diagram illustrating such a modification.

As shown the relay CRA is connected in series with line wire 11, while this relay is of a type the contacts of which will pick up when and only when energy flows through the relay winding from right to left. Contacts 14 and 15 of relay IRA, when released, establish connection between the line wires 10 and 11 so that on the supply of master code to the line wires this energy can flow through the winding of relay CRA and operate the relay. On release of relay CRA and consequent picking up of relay IRA, feed-back energy is supplied to the line wires 10 and 11 in series with the winding of relay CRA, while the direction of flow of feed-back energy through the relay CRA is such that it is ineffective to pick up the relay contacts.

The modification shown in Fig. 3 is applicable to the species shown in either Fig. 1 or Fig. 2.

Modification shown in Fig. 4

In the modifications shown in Figs. 1, 2 and 3 an impulse relay IRA is employed to supply impulses of feed-back energy to the line wires 10 and 11. The necessity for the relay IRA may be eliminated by employing a coding relay CRA of proper design, and Fig. 4 is a diagram showing a system which does not require an impulse relay.

In the modification shown in Fig. 4 the relay CRA is connected directly across the line wires 10 and 11. The apparatus of Fig. 4 is otherwise the same as that shown in Fig. 1.

In operation on picking up of the contacts 20 and 21 of coding relay CR energy is supplied

over the line wires 10 and 11 to the relay AR and CRA. This energy is of such polarity that it causes the contact 21 of relay AR to move to its right-hand or reverse position, while it causes the contacts of relay CRA to pick up.

On release of the contacts of relay CR the supply of energy to the line wires 10 and 11 and to the relays CRA and AR is cut off and the contacts of the relay CRA release, while the flux in the cores of the relays CRA and AR collapses, thereby inducing in the relay windings an impulse of energy which is of such polarity that energy continues to flow in the same direction that it had been flowing before the supply of energy to the relay winding was interrupted. Accordingly, the energy induced in the winding of relay AR flows from right to left, while the energy induced in relay CRA also flows from right to left.

At this time the windings of relays CRA and AR are connected in series and energy induced in the winding of one of these relays flows through the winding of the other relay. The energy supplied from relay CRA to relay AR flows through the winding of relay AR from left to right and thus tends to move the contact 21 of relay AR from its reverse to its normal position. The relays CRA and AR and the other portions of the combination are proportioned so that the impulse of energy supplied from relay CRA to relay AR on interruption of the supply of energy to the line wires is of such value as to move the contact of relay AR to its normal position, while the relay AR is of such design that its contact, when moved to either position, remains in that position until energy of the polarity effective to move the relay contact to its other position is supplied to the relay winding.

The impulse of energy induced in the winding of relay AR on interruption of the supply of energy to line wires 10 and 11 is supplied to the winding of relay CRA and flows through this winding from left to right. The relays AR and CRA may be so proportioned that the impulse of energy supplied from relay AR to relay CRA is too small in value to operate the relay CRA, while the relay CRA may be of the polar biased type the contacts of which when released will pick up only when energy flows through the relay winding from right to left, that is in the opposite direction to that of the energy supplied from the relay AR.

It will be seen that each time the contacts of relay CR are closed energy supplied to the line wires 10 and 11 moves the contact 21 of relay AR to its right-hand or reverse position and picks up the contacts of relay CRA. Each time the contacts of relay CR release the contacts of relay CRA release, while energy induced in the winding of relay CRA is supplied to relay AR and moves contact 21 of the relay from its right-hand to its left-hand position. Accordingly, as long as the block section is vacant relay AP remains picked up, while relay CRA is operated by coded energy.

When a train advances into section 1BT track relay 1BTR releases and its contacts 38 and 39 interrupt the circuit of relay CRA and connect line wires 10 and 11 to relay CRB. Relay CRA, therefore, ceases to follow code, while energy from the winding of this relay is no longer supplied to relay AR.

After release of relay 1BTR relay CRB is operated by coded energy supplied to the line wires 10 and 11, while each time the supply of energy to relay CRB is interrupted an impulse of energy

is induced in the relay winding and is supplied therefrom over wires 10 and 11 to relay AR.

If relay AP is employed only to control the supply of alternating current cab signal control energy to the rails of section 1DT, it is unnecessary to have this relay release when section 1BT is occupied and the relay CRB may be proportioned so that the impulse of energy supplied therefrom to relay AR will operate relay AR in the same manner that relay AR was operated by energy supplied from relay CRA. Accordingly, when relay 1BTR releases and transfers connection of line wires 10 and 11 from relay CRA to relay CRB, the relay AR continues to operate and maintain relay AP picked up.

If relay AP is employed to control the supply of energy to the lamps of signal 8S it may be preferred to have the relay AP release as soon as section 1BT is occupied. If this method of operation is desired the relay CRB may be proportioned so that the impulse of energy supplied therefrom to relay AR on interruption of the supply of energy to line wires 10 and 11 is of too small value to operate the relay. Accordingly, when relay 1BTR releases and transfers connection of the line wires 10 and 11 from relay CRA to relay CRB energy for moving the contact of relay AR to its normal position is no longer supplied to relay AR and its contact 21 remains in its reverse position and relay AP releases.

When the train advances into section 1DT track relay 1DTR releases and its contacts 52 and 53 interrupt the line wires 10 and 11 to cut off the supply of master code over these line wires, and to also cut off the supply of impulses of feed-back energy over the line wires 10 and 11 to the relay AR so that it ceases to establish the circuit for relay AP and its contacts release if they have not already done so.

When the block section is vacated master code is again supplied over line wires 10 and 11 to relay CRA and it operates to supply coded energy to the rails of section 1AT, while impulses of feed-back energy are supplied over line wires 10 and 11 to relay AR to operate it and energize the relay AP.

The operation of the system shown in Fig. 4 is substantially the same as that shown in Fig. 1 except that in the system shown in Fig. 4 the supply of feed-back energy over the line wires 10 and 11 is not cut off when a train enters section 1AT, but is maintained at least until section 1BT is occupied.

Modification shown in Fig. 5

In the arrangement as shown in Fig. 1 the supply of feed-back energy over the line wire 10 and 11 is cut off as soon as a train enters section 1AT. This insures that the lamps of signal 8S will be lighted as soon as a train enters the adjacent block section in the rear, but it also causes alternating current energy to be supplied to the rails of section 1DT as soon as section 1AT is occupied. It may be desired to have the lamps of signal 8S lighted as soon as section 1AT is occupied, but to defer the supply of alternating current energy to section 1DT until the train enters that section, and the modification shown in Fig. 5 provides for this method of operation.

The modification shown in Fig. 5 has two feed-back detector relays. These are relay ARN, which is operated by feed-back energy of normal polarity, and relay ARR, which is operated by

feed-back energy of reverse polarity. The relays ARN and ARR are of the polar biased neutral type the contacts of which pick up only when energy of a particular polarity is supplied to the relay. The relays ARN and ARR have line windings which are connected across the line wires 10 and 11 in series when the relay CR is released, while each of these relays has a holding winding to which energy is supplied when the relay contacts are picked up and the contacts of relay CR are released. The relay ARN controls the supply of energy to slow release relay APN, and relay ARR controls the supply of energy to slow release relay APR.

The relay APA, which is governed by feed-back energy supplied over the rails of section 7AT controls the polarity of the feed-back energy supplied to line wires 10 and 11 on operation of relay IRA so that energy of normal or reverse polarity is supplied according as relay APA is picked up or released.

The coding relay CRB has associated therewith feed-back supply means including an impulse transformer ITB and an impulse relay IRB which operate to cause impulses of feed-back energy of reverse polarity to be supplied to the line wires 10 and 11 when relay CRB is operated by coded energy.

The equipment for section 7AT is the same in construction and operation as that for the corresponding section of the system shown in Fig. 1.

The equipment of Fig. 5 is shown in the condition which it assumes when the track stretch is vacant. At this time energy of 180 code frequency is supplied to the coding relay CR, and when its contacts are picked up energy is supplied over front contacts 20 and 21 to line wires 10 and 11, from which it is supplied over back contacts 14 and 15 of relay IRA to relay CRA. The relay CRA, therefore, operates to cause energy to be supplied to section 7AT so that feed-back energy is supplied over the section rails to operate relay ARA and maintain the contacts of relay APA picked up so that the feed-back energy supplied to the line wires 10 and 11 is of normal polarity.

On release of the contacts of relay CR the relays ARN and ARR are connected across the line wires 10 and 11, while relay CRA releases and relay IRA picks up to cause an impulse of feed-back energy of normal polarity to be supplied over the line wires to relays ARN and ARR. This impulse of energy picks up the contacts of relay ARN and its contact 60 establishes a circuit for the relay holding winding. This circuit includes back contact 26 of relay CR and keeps the contacts of relay ARN picked up until the coding relay contacts pick up. When relay ARN picks up its contact 61 establishes the circuit of slow release relay APN and its contact 62 is picked up to interrupt the circuit of the lamps of signal 8S, while its contact 63 interrupts the supply of energy to track transformer 7DTT.

On continued coding operation of relay CR relays APA and APN are maintained picked up, while at this time relay CRB is deenergized.

When a train moving in the normal direction of traffic enters section 7AT the supply of feed-back energy over the section rails is cut off and relay APA releases and changes the feed-back energy supplied to line wires 10 and 11 from normal to reverse polarity, while it also establishes the circuit of the track transformer 7ATT so that cab signal control energy is supplied to the

rails of section 7AT. In this modification the relay APA does not control the supply of energy to the impulse transformer IT, and relay IRA continues to operate after release of relay APA.

On the supply of feed-back energy of reverse polarity to the line wires 10 and 11 relay ARN ceases to operate, while relay ARR now operates. Accordingly, relay APR picks up and relay APN releases, and the operating times of the relays APN and ARN are such that APR picks up before ARN releases.

On release of relay APN its contact 62 establishes the circuit for supplying energy to the lamps of signal 8S so this signal is lighted and provides an indication of traffic conditions in advance. On release of relay APN its back contact 63 is closed, but the circuit of the track transformer 7DTT is interrupted by front contact 65 of relay APR so energy is not supplied to the track transformer 7DTT at this time. This is desirable since section 7DT is not occupied and it is unnecessary to supply cab signal control energy to the rails of this section until the section is occupied.

When the train advances into section 7BT track relay 7BTR releases and its contacts 38 and 39 cut off the supply of energy over line wires 10 and 11 to relay CRA and connect line wires 10 and 11 to relay CRB. Accordingly, relay CRB now operates and causes coded alternating current to be supplied to track transformer 7DTT, as explained in connection with the system shown in Fig. 1 of the drawings. In addition, on operation of relay CRB energy is supplied through an impulse transformer ITB to an impulse relay IRB and it operates to supply impulses of feed-back energy of reverse polarity to the line wires 10 and 11 from a suitable source of current, such as a battery. The feed-back energy of reverse polarity supplied to the line wires 10 and 11 operates relay ARR and maintains relay APR energized to thereby prevent the supply of energy to track transformer 7DTT.

When the train advances into section 7CT track relay 7CTR releases and its contacts 48 and 49 connect line wires 10 and 11 to relay CRB so that relay CRB continues to operate and feed-back energy continues to be supplied to the line wires 10 and 11 so that relay APR is maintained energized and prevents the supply of energy to track transformer 7DTT. In addition, as explained in connection with the system shown in Fig. 1, on release of relay 7CTR the supply of energy to transformer 7DTT is cut off, while energy is supplied to transformer 7CTT.

When the train advances into section 7DT track relay 7DTR releases and its contacts 52 and 53 interrupt the line wires 10 and 11 so that relay CRB ceases to follow code and the supply of feed-back energy over the line wires to relay ARR is cut off. Accordingly, relay APR releases and establishes the circuit of track transformer 7DTT so that coded cab signal control energy is supplied to the rails of section 7DT to operate the cab signal apparatus on the locomotive in that section.

When the train vacates block section 7T the track relays for the sections 7BT, 7CT and 7DT pick up and establish the circuit of the line wires 10 and 11 with the result that relay CRA operates to supply energy to section 7AT, while feed-back energy of normal polarity is supplied over the line wires and operates relay ARN to pick up relay APN and cut off the supply of energy to

the lamps of signal 8S and to the track transformer IDTT.

From the foregoing it will be seen that the system shown in Fig. 5 operates so that the lamps of signal 8S are lighted as soon as a train enters the adjoining track section in the rear, but that alternating current cab signal control energy is supplied to each of the track sections only when that section is occupied.

In the systems shown in Figs. 2, 4 and 5, the means for controlling the highway crossing signals is not shown, but these may be governed by apparatus similar to that shown in Fig. 1, or by other appropriate apparatus well known in the art.

While each of the modifications of the invention has been illustrated and described in connection with a block section which is divided in a particular manner for the control of the crossing signals, the invention is not limited to the specific arrangement of track sections shown, and it is contemplated that the track sections may be arranged in other ways if the location of the highway intersection within the block section makes a different arrangement of the track sections necessary or desirable.

Although we have herein illustrated and described only one form of railway signaling system embodying our invention, together with several modifications which we may employ, it is understood that various changes and modifications may be made therein within the scope of the appended claims without departing from the spirit and scope of our invention.

Having thus described our invention, what we claim is:

1. In combination, a stretch of railway track having track rails divided by insulated joints into a first, a second and a third track section through which are operated in the order named locomotives equipped with cab signal apparatus responsive to the flow of coded alternating current in the track rails, a pair of line wires substantially coextensive with said second and third track sections, a first coding relay controlling the supply of coded alternating current to the rails of said first track section, a second coding relay controlling the supply of coded alternating current to the rails of said second track section, a third coding relay controlling the supply of coded alternating current to the rails of said third track section and controlling the supply of coded energy to said line wires, means governed by traffic conditions in advance of said third section for at times supplying energy of a first code frequency and at other times supplying energy of a second code frequency to said third coding relay, means effective according as said second track section is vacant or is occupied to permit energy to be supplied over said line wires to said first or said second coding relay, and means effective when said third track section is occupied to prevent the supply of coded energy over said line wires.

2. In combination, a stretch of railway track having track rails divided by insulated joints into a first, a second and a third track section through which are operated in the order named locomotives equipped with cab signal apparatus responsive to the flow of coded alternating current in the track rails, a pair of line wires substantially coextensive with said second and third track sections, means including a front contact of a first coding relay for supplying alternating current to the rails of said first track section,

means including a front contact of a second coding relay for supplying alternating current to the rails of said second track section, a third coding relay controlling the supply of alternating current to the rails of said third track section and controlling the supply of coded energy to said line wires, means governed by traffic conditions in advance of said third track section for at times supplying energy of a first code frequency and at other times supplying energy of a second code frequency to said third coding relay, means effective according as said second track section is vacant or is occupied to permit energy to be supplied over said line wires to said first or said second coding relay, and means effective when said third track section is occupied to prevent the supply of coded energy over said line wires.

3. In combination, a stretch of railway track having track rails divided by insulated joints into a first, a second and a third track section through which are operated in the order named locomotives equipped with cab signal apparatus responsive to the flow of coded alternating current in the track rails, a pair of line wires substantially coextensive with said second and third track sections, a first coding relay controlling the supply of coded alternating current to the rails of said first track section, a second coding relay controlling the supply of coded alternating current to the rails of said second track section, a third coding relay controlling the supply of coded alternating current to the rails of said third track section and controlling the supply of coded energy to said line wires, means governed by traffic conditions in advance of said third track section for at times supplying energy of a first code frequency and at other times supplying energy of a second code frequency to said third coding relay, means effective only when said second section is vacant to connect said line wires to said first coding relay and effective when said second track section is occupied to connect said line wires to said second coding relay, means effective when said line wires are connected to said first coding relay for supplying feed-back energy to the line wires in the intervals between the impulses of energy supplied to the line wires by said third coding relay, means effective when said third track section is occupied to interrupt the circuit of said line wires, and means responsive to feed-back energy supplied over said line wires and controlling the supply of alternating current to the rails of said third track section.

4. In combination, a stretch of railway track having track rails divided by insulated joints into a first, a second and a third track section through which are operated in the order named locomotives equipped with cab signal apparatus responsive to the flow of coded alternating current in the track rails, a pair of line wires substantially coextensive with said second and third track sections, a first coding relay controlling the supply of coded alternating current to the rails of said first track section, a second coding relay controlling the supply of coded alternating current to the rails of said second track section, a third coding relay controlling the supply of coded alternating current to the rails of said third track section and controlling the supply of coded energy to said line wires, means governed by traffic conditions in advance of said third track section for at times supplying energy of a first code frequency and at other times supplying energy of a second code frequency to said third coding relay, means effective only when said second track

section is vacant to connect said line wires to said first coding relay and effective when said second track section is occupied to connect said line wires to said second coding relay, means associated with said line wires for supplying feed-back energy to said line wires in the intervals between the impulses of energy supplied to the line wires by said third coding relay, means effective when said third track section is occupied to interrupt the circuit of said line wires, and means responsive to feed-back energy supplied over said line wires and controlling the supply of alternating current to the rails of said third track section.

5. In combination, a stretch of railway track having track rails divided by insulated joints into a first, a second, a third and a fourth track section through which are operated in the order named locomotives equipped with cab signal apparatus responsive to the flow of coded alternating current in the track rails, a pair of line wires substantially coextensive with said second, third and fourth track sections, a first coding relay controlling the supply of coded alternating current to the rails of said first track section, a second coding relay controlling the supply of coded alternating current to the rails of the second and third track sections, a third coding relay controlling the supply of coded alternating current to the rails of said fourth track section and controlling the supply of coded energy to said line wires, means governed by traffic conditions in advance of said fourth track section for at times supplying energy of a first code frequency and at other times supplying energy of a second code frequency to said third coding relay, means effective only when said second and third track sections are both vacant for connecting said line wires to said first coding relay and effective when said second or said third track section is occupied to connect said line wires to said second coding relay, means effective only when the third track section is vacant to establish the circuit controlled by said second coding relay for supplying alternating current to the rails of said second track section and effective only when said third track section is occupied to establish the circuit controlled by said second coding relay for supplying alternating current to the rails of said third track section, and means effective when said fourth track section is occupied to prevent the supply of coded energy over said line wires.

6. In combination, a first and a second block section of railroad track through which are operated locomotives equipped with cab signal apparatus responsive to the flow of coded alternating current in the section rails, a signal including a lamp governing entrance of trains into the second block section from the first block section, the rails of said first block section being divided into a plurality of track sections including a first and a second track section which are traversed in the order named by a train traveling in the normal direction, a pair of line wires governed by traffic conditions in said second track section, a coding relay operated by coded energy supplied over said line wires and controlling the supply of alternating current to the rails of said first track section, means governed by traffic conditions in said second block section for supplying coded alternating current to the rails of said second track section and for supplying coded energy to said line wires, means for supplying feed-back energy to said line wires in the intervals between the impulses of energy

supplied to said line wires by the means governed by traffic conditions in said second block section, and means responsive to feed-back energy supplied over said line wires and controlling the supply of energy to said signal lamp.

5. In combination, a first and a second block section of railroad track through which are operated locomotives equipped with cab signal apparatus responsive to the flow of coded alternating current in the section rails, a signal including a lamp governing entrance of trains into the second block section from the first block section, the rails of said first block section being divided into a plurality of track sections including a first and a second track section which are traversed in the order named by a train traveling in the normal direction, a pair of line wires governed by traffic conditions in said second track section, a coding relay operated by coded energy supplied over said line wires and controlling the supply of alternating current to the rails of said first track section, means governed by traffic conditions in said second block section for supplying coded alternating current to the rails of said second track section and for supplying coded energy to said line wires, means governed by traffic conditions in said first track section for supplying feed-back energy to said line wires in the intervals between the impulses of energy supplied to said line wires by the means governed by traffic conditions in said second block section, and means responsive to feed-back energy supplied over said line wires and controlling the supply of energy to said signal lamp.

8. In combination, a first and a second block section of railroad track through which are operated locomotives equipped with cab signal apparatus responsive to the flow of coded alternating current in the section rails, a signal including a lamp governing entrance of trains into the second block section from the first block section, the rails of said first block section being divided into a plurality of track sections including a first and a second track section which are traversed in the order named by a train traveling in the normal direction, a pair of line wires governed by traffic conditions in said second track section, a coding relay operated by coded energy supplied over said line wires and controlling the supply of alternating current to the rails of said first track section, means governed by traffic conditions in said second block section for supplying coded alternating current to the rails of said second track section and for supplying coded energy to said line wires, means for supplying feed-back energy to said line wires in the intervals between the impulses of energy supplied to said line wires by the means governed by traffic conditions in said second block section, means for causing the feed-back energy supplied to said line wires to be of normal or reverse polarity according as said first track section is vacant or is occupied, means responsive to feed-back energy of normal polarity only supplied over said line wires for interrupting the supply of energy to said signal lamp, and means responsive to feed-back energy of either polarity supplied over said line wires for preventing the supply of alternating current to the rails of said second track section.

9. In combination, a stretch of railway track having track rails divided by insulated joints into a first, a second and a third track section through which are operated in the order named

locomotives equipped with cab signal apparatus responsive to the flow of coded alternating current in the track rails, a pair of line wires substantially coextensive with said second and third track sections, a first coding relay controlling the supply of coded alternating current to the rails of said first track section, a second coding relay controlling the supply of coded alternating current to the rails of said second track section, means for supplying coded alternating current energy to the rails of said third track section and for supplying coded energy to said line wires, means effective according as said second section is vacant or is occupied to permit energy to be supplied over said line wires to said first or said second coding relay, and means effective when said third section is occupied to prevent the supply of coded energy over said line wires.

10. In a railway signaling system, in combination, a stretch of railroad track divided into a first, a second and a third block section through which are operated in the order named locomotives equipped with cab signal apparatus responsive to the flow of coded alternating current in the section rails, the rails of the second block section being divided into a plurality of track sections including a first and a second track section, said first track section being located at the end of the block section adjacent said third block section, a line circuit governed by traffic conditions in said first track section, means governed by traffic conditions in said third block section for supplying coded alternating current to the rails of said first track section and for supplying coded energy to said line circuit, a first coding relay controlling the supply of coded alternating current to the rails of said first block section, a second coding relay controlling the supply of coded alternating current to the rails of said second track section, and means effective according as said second track section is vacant or is occupied to connect said line circuit to said first or said second coding relay.

11. In a railway signaling system, in combination, a stretch of railway track divided into a forward and a rearward block section and through which are operated locomotives equipped with cab signal apparatus responsive to the flow of coded alternating current in the section rails, the rails of said forward block section being divided into a plurality of track sections including a forward and a rearward track section, a line circuit governed by traffic conditions in said forward track section, means for supplying coded alternating current to the rails of said forward track section and for supplying coded energy to said line circuit, a first coding relay controlling the supply of coded alternating current to the rails of said rearward block section, a second coding relay controlling the supply of coded alternating current to the rails of said rearward track section, and means effective according as said second track section is vacant or is occupied to connect said line circuit to said first or said second coding relay.

12. In a railway signaling system, in combination, a stretch of railway track divided into a forward, an intermediate and a rearward block section and through which are operated locomotives equipped with cab signal apparatus re-

sponsive to flow of coded alternating current in the section rails, the rails of said intermediate section being divided into a plurality of track sections including a forward and a rearward track section, a line circuit governed by traffic in said forward track section, a signal including a lamp controlling entrance of trains into said forward block section, means governed by traffic conditions in said forward block section and controlling a circuit for supplying coded alternating current to the rails of said forward track section and also controlling the supply of coded energy to said line circuit, a first coding relay controlling the supply of coded alternating current to the rails of said rearward block section, a second coding relay controlling the supply of coded alternating current to the rails of said rearward track section, means effective according as said rearward track section is vacant or is occupied to connect said line circuit to said first or said second coding relay, means associated with said first coding relay and operative on the supply of coded energy over said line circuit to said relay to supply feed-back energy to the line circuit in the intervals between the impulses of energy supplied to said line circuit by the means governed by traffic in said forward block section, and means responsive to feed-back energy supplied over said line circuit and controlling the supply of energy to said signal lamp.

13. In a railway signaling system, in combination, a stretch of railway track divided into a forward, an intermediate and a rearward block section and through which are operated locomotives equipped with cab signal apparatus responsive to flow of coded alternating current in the section rails, the rails of said intermediate section being divided into a plurality of track sections including a forward and a rearward track section, a line circuit governed by traffic in said forward track section, a signal including a lamp controlling entrance of trains into said forward block section, means governed by traffic conditions in said forward block section and controlling a circuit for supplying coded alternating current to the rails of said forward track section and also controlling the supply of coded energy to said line circuit, a first coding relay controlling the supply of coded alternating current to the rails of said rearward block section, a second coding relay controlling the supply of coded alternating current to the rails of said rearward track section, means effective according as said rearward track section is vacant or is occupied to connect said line circuit to said first or said second coding relay, means associated with said first coding relay and operative on the supply of coded energy over said line circuit to said relay to supply feed-back energy to the line circuit in the intervals between the impulses of energy supplied to said line circuit by the means governed by traffic in said forward block section, and means responsive to feed-back energy supplied over said line circuit and controlling the supply of energy to said signal lamp and the circuit for supplying alternating current to the rails of said forward track section.
